CLAIM

The ornamental design for a candy box, as shown and described.

DESCRIPTION

FIG. 1 is a perspective view of the candy box of the invention.

FIG. 2 is a plan view of the top surface of the candy box of the invention shown in FIG. 1.

FIG. 3 is an elevational view of the front side of the candy box shown in FIG. 1. The rear side is a mirror image of the front side.

FIG. 4 is a plan view of the bottom surface of the candy box of the invention shown in FIG. 1; and,

FIG. 5 is an elevational view of the right side of the candy box shown in FIG. 1. The left side is a mirror image of the right side.
